UNITED STATES PATENT OFFICE.

ADOLF BOGE, OF SOLINGEN, GERMANY.

LOCK.

1,428,553.

Specification of Letters Patent. Patented July 25, 1922.

Application filed August 26, 1921. Serial No. 495,570.

To all whom it may concern:

Be it known that I, ADOLF BOGE, a citizen of the German Republic, residing at Solingen, Rhenish Prussia, Germany, have invented certain new and useful Improvements in Locks (for which I have filed applications in Germany Dec. 1, 1914, and June 2, 1920; France July 10, 1920; Sweden June 30, 1920, and Switzerland July 17, 1920), of which the following is a specification.

The subject-matter of my co-pending application No. 495,569 is a lock provided with a key-bit (therein termed a "rotary element") remaining continuously in the main lock and coacting with two cylinder locks mounted one at each side of the main lock, so that by the insertion of the key into either cylinder lock said key-bit becomes 20 coupled with this cylinder lock and can thus be turned to actuate the bolt.

The key-bit has slotted, sleeve-like ends which are engaged by slotted, pin-like extensions on the two rotary cylinders of the 25 side locks, whereby the end of the key can penetrate into the key-bit and drive the same directly. Whereas for the embodiment of the invention claimed in this co-pending application a specially designed 30 main lock in combination with said key-bit is described, according to the present invention, said key-bit or its equivalent and said cylinder locks, connected as above described, may be employed in combination 35 with any other lock than that specifically claimed in the co-pending application.

For example, in the modification herein-after described, a key-bit is employed which has the sleeve-like form from end to end, 40 and not merely sleeve-like ends as in the co-pending application, and is provided with an external lug for actuating the bolt. Where an existing lock is provided with the key-bit, this lock can be converted into a 45 safety or cylinder lock according to the present invention by connecting to it two cylinder locks substantially in the manner above described.

In the new lock, the journalling for the 50 key-bit axle thus completed and strengthened is preferably not, as usual, in the lock wall, but on the pins of the rotary cylinders which engage the key-bit in the interior of its axle. There is thus obtained not only 55 a good bearing for the key-bit independent

of the lock walls, but also the further advantage that the key, during the locking movement, is at the same time guided for a considerable part of its length in the rotary cylinder and key-bit axle, and in that way 60 mechanical stressing of the key is considerably reduced. Finally this arrangement has the further advantage that the cylinder locks are each inserted into the lock walls by means of a spigot or annular element 65 concentric with their rotary axis and consequently they can be secured against displacement in accurately concentric positions.

Two embodiments of the invention are 70 shown by way of example in the accompanying drawing, one being a mortise lock and the other a box-lock. In this drawing—

Fig. 1 shows the mortise lock embodiment 75 in vertical section,

Figs. 2 and 3 show two views of the appertaining key-bit,

Fig. 4 shows the rim-lock embodiment 80 and

Figs. 5 and 6 show the appertaining key-bit.

50 are the casing walls of the main lock, on both sides of which are arranged cylinder locks 51 and 52 provided in known manner with pin tumblers and fastened by means of a common screw 53. The two rotary cylinders 53, 54 are each provided at their inner ends with a cylindrical extension 55, 56, respectively, whereon the key-bit 57 which remains in the lock is journaled by means of its axle 58. This axle is provided with a slit or slot 59 extending longitudinally through it, which slot corresponds to the slots in the two rotary cylinders for receiving the key, so that the key can be inserted through the one, as also the other rotary cylinder, and the inner lock walls 50, passing right through directly into the key-bit. By the insertion of the key the 95 particular rotary cylinder is coupled with the key-bit 57 and, as the drawing shows, the key for a considerable portion of its length is in engagement with the rotary cylinder and the key-bit sleeve, so that mechanical stressing of the key will be small and even when the lock is stiff in action breakage of the key in the lock need not be contemplated. When the key is withdrawn the key-bit is turnable and is then 100 105 110

resiliently held in the middle position shown by means of a snap-in ball 61 acted on by a spring 60, so that the slot in the key bit axle and that in either rotary cylinder are located exactly opposite each other and proper insertion of the key is ensured, without opening or closing from either side of the door being prevented. The cylinder locks 52, 51 are provided on their rear sides each with an annular lip or spigot 62, 63, respectively, by means of which they engage in a corresponding hole in the lock wall and are thus secured in exactly concentric positions against displacement.

15 The rim lock shown in Figs. 4-6 corresponds in all its essential parts with the above described mortise-lock. The corresponding parts are therefore indicated by the same reference letters so that a special 20 description of this embodiment will be unnecessary.

I claim:

1. A safety lock comprising in combination a main lock, a key-bit remaining continuously therein and a cylinder lock mounted on each side of the main lock, the rotary cylinder of each side lock and the key-bit telescoping each other and having longitudinal, registering slots for jointly receiving the 30 key.

2. A safety lock comprising in combination a main lock, a key-bit remaining continuously therein and a cylinder lock mounted on each side of the main lock, the rotary cylinder of each side lock and the key-bit telescoping each other and having longitudinal registering slots for jointly receiving the key, which slots pass right through the telescoping joint.

40 3. A safety lock comprising in combination a main lock, a key-bit remaining continuously therein and a cylinder lock mounted on each side of the main lock, a rotary cylinder of each side lock and the key-bit 45 telescoping each other and having longitudinal, registering slots for jointly receiving the key, and the key-bit being journaled solely at and by the telescoping joints.

4. A safety lock comprising in combination a main lock, a sleeve-like key-bit remaining continuously therein and a cylinder lock mounted on each side of the main lock, the rotary cylinder of each side lock having a pin-like extension telescoping into 55 the key-bit, and each rotary cylinder and the key-bit having longitudinal, registering slots for jointly receiving the key.

5. A safety lock comprising in combination a main lock, a sleeve-like key-bit remaining continuously therein and a cylinder lock mounted on each side of the main lock, a rotary cylinder of each side lock having a pin-like extension telescoping into the key-bit, and each rotary cylinder and the key-bit 60 having longitudinal, registering slots for

jointly receiving the key, which slots pass right through the telescoping joint.

6. A safety lock comprising in combination a main lock, a key-bit remaining continuously therein and a cylinder lock mounted on each side of the main lock, the casing of each side lock having a spigot projection engaging in the casing of the main lock, and a rotary cylinder of each side lock and the key-bit telescoping each other and having longitudinal, registering slots for jointly receiving the key.

7. A safety lock comprising in combination a main lock, a key-bit remaining continuously therein and a cylinder lock mounted on each side of the main lock, the rotary cylinder of each side lock and the key-bit telescoping each other and having longitudinal registering slots for jointly receiving the key, and resiliently influenced means 85 for holding the slots in registration.

8. A safety lock comprising in combination a main lock, a key-bit remaining continuously therein and a cylinder lock mounted on each side of the main lock, the rotary cylinder of each side lock and the key-bit telescoping each other and having longitudinal, 90 registering slots for jointly receiving the key, and a spring-controlled ball for holding the slots in registration.

9. A safety lock comprising in combination a main lock, a key-bit remaining continuously therein, a cylinder lock mounted on each side of the main lock, the rotary cylinder of each side lock and the key-bit telescoping each other and having longitudinal, 100 registering slots for jointly receiving the key, the casing of a cylinder lock having a radial hole and the key-bit a socket below the hole, a compression spring within the radial hole and a ball at the inner end thereof and adapted to engage the socket in the key-bit when the slots are registered.

10. A safety lock comprising in combination a main lock, a key-bit remaining continuously therein, a cylinder lock mounted at each side of the main lock, the casing of each side lock having a spigot engaging in the casing of the main lock, and a screw 110 commonly holding together the main lock and side locks, the rotary cylinder of each side lock and the key-bit telescoping each other and having longitudinal, registering slots for jointly receiving the key.

11. A safety lock comprising in combination a main lock, a key-bit remaining continuously therein, and a cylinder lock mounted at each side of the main lock and having a lug on its casing, the casing of each side lock also having a spigot engaging in the 125 casing of the main lock, and a screw commonly holding together the main lock and the lugs on the side locks, the rotary cylinder of each side lock and the key-bit telescoping each other and having longitudinal, 130

registering slots for jointly receiving the key.

12. A safety lock comprising in combination a main lock, a key-bit of continuous tube form remaining always in the main lock and a cylinder lock mounted at each side of the main lock, the rotary cylinder of each side lock having a pin-like extension telescoping into the key-bit, and each rotary cylinder and the key-bit having longitudinal, registering slots for jointly receiving the key, the slot in the key-bit extending outwardly to such a distance that the peripheral portion of the key-bit tube remains entire.

13. A safety lock comprising in combination a main lock, a key-bit of continuous tube form remaining always in the main lock and a cylinder lock mounted at each side of the main lock, the rotary cylinder of each side lock having a pin-like extension telescoping into the key-bit, and each rotary cylinder and the key-bit having longitudinal, registering slots for jointly receiving the key, the slot in the said pin-like extension extending inwardly therein to leave substantial distance between its bottom and

the periphery of the extension and the slot in the key-bit extending outwardly to such a distance that the peripheral portion of the key-bit tube remains entire.

14. A safety lock comprising in combination a main lock, a key-bit of continuous tube form remaining always in the main lock and a cylinder lock mounted at each side of the main lock, the rotary cylinder of each side lock having a pin-like extension telescoping into the key-bit, and each rotary cylinder and the key-bit having longitudinal, registering slots for jointly receiving the key, which slots pass right through the telescoping joint, the slot in said pin-like extension extending inwardly therein to leave substantial distance between its bottom and the periphery of the extension and the slot in the key-bit extending outwardly to such a distance that the peripheral portion of the key-bit tube remains entire.

In testimony whereof, I affix my signature in the presence of two witnesses.

ADOLF BOGE.
